UNITED STATES PATENT OFFICE.

MAURICE E. STRIEBY, OF MILLBURN, NEW JERSEY, ASSIGNOR TO AMERICAN TELEPHONE AND TELEGRAPH COMPANY, A CORPORATION OF NEW YORK.

PROGRAM-SELECTING CIRCUITS.

Application filed December 10, 1923. Serial No. 679,721.

This invention relates to transmission systems for transmitting programs over wires, and more particularly to arrangements for the selection of programs for such systems.

Where wire lines, such as ordinary telephone lines, for example, are used for the transmission of programs, such as news, lectures, concerts, and the like, it is desirable that some arrangement be provided whereby the subscriber may automatically select the particular program which he desires to hear. In accordance with the present invention, it is proposed to accomplish this result by providing a selective switch at the central office which may be directly controlled by the subscriber to connect the terminals of the subscriber's line to the terminals of any one of a number of trunks each leading to a different program.

By the use of a directly controlled selective switch for selecting a program, it becomes immaterial whether the program be transmitted at voice frequencies or carrier frequencies, and it also becomes immaterial whether the several programs be transmitted at the same frequency or whether different carrier frequencies are used for different programs. The directive switch may be controlled by impulses or groups of impulses of alternating current and the source of current for operating the switches may be located either at the central station or at the subscriber's station. Preferably the switches are operated in accordance with the present invention over the sides of the line in series.

The invention will now be more fully understood when read in connection with the accompanying drawing, Figure 1 of which illustrates how a directive switch operated by alternating current may be used to select programs transmitted at ordinary telephonic frequencies; Fig. 2 of which shows how a similar switch may be used to select carrier frequency programs, and Fig. 3 of which shows a circuit arrangement similar to that of Fig. 2 but so arranged that the alternating current source for operating the switches will be located at the central station.

Referring to Fig. 1, L designates an ordinary telephone transmission line terminating in the usual subscriber's set S at one end and terminating at the central office in the

usual switching jack J. Normally the telephone line L is connected over the contacts of a cut-off relay CO to the windings of the line relay LR. The line relay, as is usual, may comprise two windings, each of about 1000 ohms. The upper winding is associated with the tip side of the line and is inductive. The lower winding is associated with the ring side of the line but is non-inductive and consequently, does not magnetize the core of the relay when current flows through said winding. The cut-off relay CO is so arranged that when it is operated the line relay LR is disconnected from the line L and the line is connected directly to the tip and ring terminals of the jack J.

In order that the line may be used for program transmission purposes during such time as it is not being used for ordinary telephone purposes, a program receiver such as the loud speaker LS is provided at the subscriber's station, said receiving device being bridged across the line through the back contact of the switchhook 10. When the substation set S is used for ordinary telephonic purposes, the removal of the receiver from the switchhook opens the circuit of the loud speaker LS so that it may not be then used for receiving programs. At the central office a pair of conductors 11 are connected from the back contacts of the cut-off relay CO to the wipers 12 of a directive switch DR. The switch DR may be stepped by means of the stepping magnet SM into connection with any one of a number of trunks A, B, C or D, leading to different voice frequency programs.

In order to operate the stepping magnet SM, a switching device such as a dial or key K is provided at the subscriber's station for sending impulses of alternating current over the line to energize the marginal stepping relay SR. The source of alternating current at the subscriber's station is bridged across the line over the back contact of the switchhook 10. The alternating current for operating the switches may be obtained from the power mains at the subscriber's premises. The alternating current relay SR is connected across the back contacts of the cut-off relay CO in parallel with the windings of the line relay LR.

The operation is as follows: When the line L is not in use for telephone purposes and the subscriber desires to hear a pro-

gram, such as C, for example, the subscriber will merely actuate the dial or key K to send impulses from the source G through the tuned bridge controlled by the key K. These impulses pass from one terminal of the transformer 13, over the key K, back contact of the switchhook 10, over the ring side of the line L, lower back contact of the cut-off relay CO, through the tuned circuit of the alternating current relay SR, over the upper back contact of the cut-off relay CO, over the tip side of the line L to the opposite terminal of the transformer 13. The ringer at the subscriber's station is ordinarily tuned to respond to a frequency of about 20 cycles per second, and since the frequency of the alternating current supplied to the power mains at the subscriber's station will usually be in the neighborhood of 60 cycles, it will be apparent that the current impressed upon the line by the key K will not operate the subscriber's bell. The line relay LR is not responsive to alternating current. The current flowing through the relay SR energizes said relay so that the impulses sent by the key K are transmitted by the relay SR to the stepping magnet SM. Accordingly, the directive switch DR is operated step by step by the mechanism conventionally indicated to advance the wipers 12 to the terminals of the trunk leading to the program C. The currents for this program are now transmitted over the wipers 12 and conductors 11, over the back contacts of the cut-off relay CO and over the line L to the loud speaker LS.

If, while the circuit is being used for program purposes, the subscriber desires to make a telephone call, he merely removes the receiver from the switchhook in the usual manner. The loud speaker LS is disconnected at the back contact of the switchhook so that the program ceases. At the same time, a low resistance circuit is established through the substation set from battery, through the upper winding of the line relay LR, over the back contact of the cut-off relay CO, over the tip side of the line L, over the switchhook 10, back over the ring side of the line L, back contact of the cut-off relay CO and through the non-inductive winding of the relay LR to ground. The line relay LR is at once energized and upon attracting its armature, causes the line lamp (not shown) to glow in the usual manner. The operator, upon noticing this signal, will insert the plug of the cord circuit into the jack J, thereby actuating the cut-off relay CO. The cut-off relay connects the line L at its front contacts to the tip and ring terminals of the jack J and at the same time disconnects the line L from the line relay LR, the stepping relay SR and the program connections 11 leading to the

switch DR. The call is then completed in the usual manner. At the end of the conversation the subscriber hangs up his receiver and the operator withdraws the plug from the jack J, releasing the cut-off relay CO. This at once connects the line L to the program connections 11 and the subscriber may continue to hear the program being transmitted.

If, while the program is being received, a telephone call should come in for line L, the operator will insert the plug of her cord into the jack J, thereby operating the cut-off relay as before. The line L will now be disconnected from the program connections 11 and will be connected over the front contacts of the cut-off relay to the terminals of the jack J. In answer to the ringing signal, the subscriber will remove his receiver from the switchhook and disconnect the loud speaker LS. It will be observed that if the line is being used for telephonic purposes it is impossible to set the directive switch DR, for the key K is disconnected as soon as the subscriber removes his receiver from the switchhook and the selecting relay SR at the central station is disconnected as soon as the cut-off relay CO is operated.

The same arrangements may be used for selecting any one of a number of carrier programs as illustrated in Fig. 2. In this case, where the programs are transmitted at carrier frequencies, it is to be observed that the line may be used simultaneously for receiving program transmission and for ordinary telephonic purposes. Consequently, the connections 11 extending to the wipers 12 of the directive switch are extended to the tip and ring sides of the line L adjacent to the armature connections of the cut-off relay, so that the operation of the cut-off relay will not disconnect the program connections 11 from the line L, the cut-off relay in this instance merely serving to disconnect the line relay LR and the stepping relay SR.

At the subscriber's station the loud speaker LS is bridged across the line independently of the switchhook 10, so that the removal of the receiver from the switchhook 10 does not disconnect the loud speaker. The circuit including the selecting key K is, however, bridged across the line over the back contact of the switchhook as before. The program cannot, therefore, be changed during the time that the telephone set is in use, it being undesirable to permit change of program at this time because the subscriber would hear the noise due to the alternating current pulses transmitted by the key K.

The carrier frequency programs may be transmitted each at a different frequency but by the use of the directive selective switch, it is possible to use the same carrier frequency for all of the programs since but

one program will be transmitted over a line at a time. At the subscriber's station it will be necessary to provide suitable detecting apparatus and in most cases amplifying apparatus, as conventionally indicated at 5 AD, in order to translate the carrier program into voice frequency currents for operating the loud speaker. No selecting apparatus is necessary at the subscriber's station even in the case of carrier transmission, except a single high pass filter conventionally indicated at HP, this filter being provided to prevent the voice frequency currents transmitted over the line from actuating 10 the loud speaker. The high pass filter will, of course, pass the carrier frequencies used for program transmission, regardless of whether the same carrier frequency is used for all of the programs or whether a 15 different carrier frequency is used for each program.

Instead of obtaining the alternating current for operating the stepping relay SR from the power mains at the subscriber's station, the current may be obtained from a 25 source G' located at the central office as shown in Fig. 3. Preferably this source will be connected through a transformer 13' at a point intermediate between the upper 30 and lower windings of the alternating current stepping relay SR. It will be observed that if the subscriber removes his receiver from the switchhook, he will be able to hear the current from the source G', as said 35 source is, in effect, bridged across the two sides of the line through the windings of the relay SR and over the back contacts of the cut-off relay CO. As soon as the operator answers his signal, however, the cut-off 40 relay CO is operated and in connecting the terminals of the line to the jack J, the cut-off relay functions to disconnect the relay SR as well as the line relay LR from the line. Consequently, the tone due to the 45 alternating current source will cease before any conversation takes place over the line. The operation of the circuit of Fig. 3 is otherwise similar to that of Fig. 2 and need not be further described.

50 It will be obvious that the general principles herein disclosed may be embodied in many other organizations widely different from those illustrated without departing from the spirit of the invention as defined 55 in the appended claims.

What is claimed is:

1. In a program distribution system, a subscriber's telephone line terminating in a subscriber's telephone apparatus at the subscriber's station, switching means at the central office whereby connections may be established between said subscriber's line and another subscriber's line, a plurality of trunks at the central office upon which programs may be impressed, a directly operated 60 switch independent of said first mentioned switching means at the central office for establishing connections between said subscriber's line and any desired trunk to the exclusion of other trunks, an alternating current responsive means for 65
- switch independent of said first mentioned switching means at the central office for establishing connections between said first mentioned line and any desired trunk to the exclusion of other trunks, an alternating current control device for operating said switch, and means to control the transmission of alternating current to said device from the subscriber's station over the two sides of said first mentioned line in series. 70

2. In a program distribution system, a subscriber's telephone line terminating in a subscriber's telephone apparatus at the subscriber's station, switching means at the central office whereby connections may be established between said subscriber's line and another subscriber's line, a plurality of trunks at the central office upon which programs may be impressed, an impulse-operated switch independent of said first mentioned 80 switching means at the central office to select any trunk to the exclusion of the others, an alternating current responsive device for controlling the operation of said switch, and means at the subscriber's station for controlling the transmission of impulses of alternating current over the two sides of said first mentioned line in series to operate said device. 85

3. In a program distribution system, a subscriber's telephone line terminating in a subscriber's telephone apparatus at the subscriber's station, switching means at the central office whereby connections may be established between said subscriber's line and another subscriber's line, a plurality of trunks at the central office upon which programs may be impressed, an impulse-operated selecting switch independent of said first mentioned switching means at the central office to select any trunk to the exclusion of the others, an alternating current responsive device for controlling said switch, an impulse sender at the subscriber's station, and means whereby said sender may control the transmission of impulses of alternating current over the two sides of said first mentioned line in series to operate said device. 100

4. In a program distribution system, an ordinary telephone subscriber's line terminating in a subscriber's telephone apparatus at the subscriber's station, switching means at the central office for establishing connections between said subscriber's line and other subscribers' lines so that telephone conversations may take place at ordinary telephonic frequencies, a plurality of trunks at the central office upon which different programs may be impressed at carrier frequencies, a directly operated switch independent of 115 said first mentioned switching means at the central office for establishing connections between said first mentioned line and any desired trunk to the exclusion of other trunks, an alternating current responsive means for 120

controlling said switch, and means at the subscriber's station to control the transmission of alternating current over the two sides of said first mentioned line in series to operate said device.

5. In a program distribution system, an ordinary telephone subscriber's line terminating in a subscriber's telephone apparatus at the subscriber's station, switching means 10 at the central office for establishing connections between said subscriber's line and other subscribers' lines so that conversations may take place at ordinary telephonic frequencies, a plurality of trunks at the central office upon which different programs may be 15 impressed at carrier frequencies, an impulse-operated switch independent of said first mentioned switching means at the central office to select any trunk to the exclusion of the others, an alternating current responsive device for the control of said switch, and means at the subscriber's station for controlling the transmission of alternating current over the two sides of said first mentioned 20 line in series to operate said device.

25

6. In a program distribution system, an ordinary telephone subscriber's line terminating in a subscriber's telephone apparatus at the subscriber's station, switching means at the central office for establishing connections between said subscriber's line and other subscribers' lines so that conversations may take place at ordinary telephonic frequencies, a plurality of trunks at the central office upon which different programs may be 30 impressed at carrier frequencies, an impulse-operated switch independent of said first mentioned switching means at the central office to select any trunk to the exclusion of the others, an alternating current responsive device for controlling said switch, an impulse sender at the subscriber's station, and means controlled by said sender for transmitting impulses of alternating current over the two sides of said first mentioned line in series to operate said device.

In testimony whereof, I have signed my name to this specification this 7th day of December, 1923.

MAURICE E. STRIEBY.
